FREDERICK L. H. SIMS, OF TORONTO, ONTARIO, CANADA.

INTERNAL-COMBUSTION MOTOR.

1,286,431.

Specification of Letters Patent.

Patented Dec. 3, 1918.

Application filed November 28, 1916. Serial No. 133,946.

To all whom it may concern:

Be it known that I, FREDERICK L. H. SIMS, of the city of Toronto, in the county of York, Province of Ontario, Canada, a subject of the King of Great Britain, have made certain new and useful Improvements in Internal-Combustion Motors, of which the following is a specification.

This invention relates particularly to the 10 means for controlling the admission of air, either in a combustible mixture or separately, and of the exhaust of the products of combustion from internal combustion motors.

15 My object is to provide a simple valve system not liable to leak and operable without complex cams or gears; to diminish the noise of valve operation; to simplify the water jacketing of the cylinder and valve; and to cheapen cylinder construction.

Further objects are to provide simple means for feeding a liquid fuel and for effecting a practically total scavenging of the cylinder after each explosion.

25 I attain the above objects and obtain other advantages by means of the constructions hereinafter specifically described and illustrated in the accompanying drawings in which—

30 Figure 1 is a longitudinal section of the cylinder and valve system of an internal combustion motor constructed in accordance with my invention;

Fig. 2 a plan view of the same, partly in 35 section;

Figs. 3 and 4 enlarged sections through the valve ring and cylinder ports showing two different positions; and

40 Figs. 5, 6 and 7 diagrammatical developments of the cylinder wall and valve ring showing various possible arrangements of the ports.

In the drawings like numerals of reference indicate corresponding parts in the 45 different figures.

1 is the cylinder, which in the main is of ordinary construction and may be water-jacketed in the ordinary manner. I prefer, however, to form the water-jacket by means

of a removable sleeve 2 secured in position 50 in any suitable manner. This sleeve is preferably welded to an annular member 3 which forms a seat for the annular valve hereinafter described. This annular seat is preferably tapered on the inside and seats 55 on tapered ribs 4 formed on the cylinder, these ribs thus support the annular seat member and at the same time provide water channels for the jacketing of the head portion of the cylinder and the valve. 60

The cylinder may be provided with the ordinary fixed head. I prefer, however, employing a head 5 movable axially of the cylinder. This head is limited in its movement outwardly by the relatively fixed head 6, for instance, by contacting with the rim 7 of the head which is screwed within the cylinder end as shown.

The movable head 5 is yieldingly pressed inwardly by means of the coil springs 8, 70 which engage both the fixed and movable head and are held in position by the studs 9 on one of the heads. The movement of the movable head toward the piston is limited by its engagement with the shoulder 39 75 formed by counterboring the cylinder, though other arrangements might, of course, be employed.

The cylinder is provided with a plurality of ports 10, which are preferably proportioned in number to the diameter of the cylinder so that the distance moved by the valve at each step will not be unduly large. For a cylinder four inches in diameter sixteen is a good number, and in larger sizes 85 larger multiples of four will be employed.

11 is the annular valve which fits on the coned outer surface of the annular seat member 3. This valve is held in position by spring pressure, preferably adjustable. For 90 this purpose I provide one or more coil springs 12 which bear against the annular valve and against a nut 13 screwed on the upper part of the annular valve seat. Preferably a collar 14 is interposed between the 95 springs and the valve, and this collar carries steadyng studs 15 for the springs.

While the annular valve may be formed in

various ways, for convenience in forming the ports therein, I prefer to form the valve in two parts *a*, *b*. The part *a* is screwed on to the part *b* as shown. Through the annular valve I form the exhaust ports 16. These preferably extend straight through to its outer surface.

If the ports are to be arranged on the system shown in Fig. 5, air ports 17 are also formed in the annular valve, but these ports, instead of extending straight through to the outer surface, extend diagonally upward, as shown in Fig. 4, through the upper surface of the annular valve.

15 The annular valve is given an intermittent stepwise movement, and in the case in which the movement is effected at the end of each stroke of the piston, the valve arrangement will be as shown in Fig. 5.

20 The exhaust ports correspond in number to the cylinder ports, in the present case sixteen being employed. The arrangement then is that following an exhaust port is an air inlet port, following that a blank space 25 corresponding to two ports, then another air port and repeat, the blank space being equivalent to twice the distance from center to center of an air and exhaust port.

As the annular valve is moved an exhaust 30 port will be in communication with the cylinder port, then an air port in communication with the cylinder port, then for two movements of the valve the cylinder port is closed off and the cycle is repeated.

35 The exhaust may be directly to the outer air where such disposal of it is not objectionable. For ordinary purposes, however, an annular exhaust chamber 18 will be fitted between the shoulders 19 on the annular 40 valve so as to maintain substantially a gas tight joint therewith. From this annular exhaust chamber an exhaust manifold may be led to any desired point.

The exhaust chamber may be made eccentric, as indicated in the plan view, to facilitate the discharge.

In Fig. 6 I show a modification in which the annular valve moves only three times in the cycle of the engine, that is, it moves 50 always on the out-stroke of the piston and alternately on the in-stroke of the piston. The arrangement of the ports of the annular valve is then as follows: first an exhaust port, then an air port, then a blank space 55 corresponding to the distance between centers of the exhaust and air ports. In this case the space between exhaust ports is divided by three instead of by four, as in the arrangement shown in Fig. 5. The air 60 ports may extend through to the outer surface of the annular valve instead of through its upper surface as in the form shown in Figs. 3, 4 and 5.

In Fig. 7 I show a further modification

in which the air and the exhaust pass 65 through the same ports in the valve, and the valve is moved only twice in each cycle, that is, on the out-stroke of the piston, the distance moved each time being half the distance between the valve ports. 70

Various means may be employed to move the valve. I show a preferred form in Fig. 2. Though the gearing may vary, the annular valve is shown as provided with sixty-four gear teeth 21 at its outer periphery below the exhaust chamber. With these gear teeth meshes the sixteen tooth pinion 22 on the upper end of the shaft 23. The lower end of this shaft carries the pin wheel 24, the studs of which mesh with the cam rib 25 on the cam wheel 26 fast on the crank shaft of the motor. A portion of this cam rib is shaped as a helix, but for the greater part of its length it does not change its position axially so that no movement of the pin wheel, 80 with which it meshes, takes place until a change of position of the valve is necessary, thus avoiding the constant running of the annular valve.

The rib stays in the same plane preferably 90 for 150°, then makes a shift of 22.5° on the circumference of the pin wheel, or half of the pitch of one of the wheel teeth, thus moving the pin wheel, which is eight toothed, one tooth and the valve one sixty-fourth of a 95 revolution. The cam rib then stays in the same plane for another 150° and shifts as before, the shift being for 30° of the circumference of the rib.

The arrangement described is not essential 100 as other arrangements which would answer the same purpose are quite possible. The one shown and described will run very easily and almost noiselessly, and is well adapted to my purpose.

105 It will be noted that the air ports of the annular valve open directly to the atmosphere, which is an arrangement best adapted for use with an engine in which the fuel is injected directly into the cylinder instead of being drawn mixed with air, through an intake manifold from a carburetor.

As I employ a movable piston head for scavenging purposes, I am enabled to use its movements, if desired, to inject the fuel. 115 For this purpose I provide the center of the fixed head with the pump cylinder 27 in which moves the plunger 28 secured to the movable head.

The pump cylinder is preferably provided 120 with a stuffing box 29 through which the plunger passes. A check valve 30 is provided in the fuel connection with the pump cylinder 27. This check valve allows of the inflow of fuel, but prevents outflow. The plunger 28 has a small bore formed through it communicating with the interior of the cylinder. A check valve 36 is also provided 125

in the plunger to prevent back flow. The movable head descends during the exhaust stroke of the piston moving the pump plunger and so filling the pump cylinder with fuel. It remains down until compression begins, then moves up as soon as the compression becomes sufficiently great, and in so doing injects into the cylinder the fuel which had previously been drawn into the pump cylinder. Thus the fuel is injected practically at the end of the compression stroke, so avoiding premature firing.

Ignition may take place either by compression of the mixture or by spark plug as desired. The movable head may also be used as a circulation pump. Ports 31 may be formed in the rim of the fixed head communicating with ports 32 in the wall of the cylinder between the ribs 4. Inwardly opening check valves 37 should be applied to the ports 31 at one side and outwardly opening check valves at the other side. Water is thus drawn in through the ports at one side as the movable head moves down, and forced out again at the other side as it moves up.

Water spaces 33 are also formed in the annular valve communicating by means of ports 34 with ports 35 formed in the valve seat. These ports, of course, are not necessarily in constant communication, but are successively brought into communication as the annular valve is moved. The arrangement of the annular valve to run on a coned seat is of great importance as it thus grinds itself to its seat and never leaks and never binds.

What I claim as my invention is:

1. In an internal combustion motor of the four-stroke cycle type the combination of a cylinder having a plurality of equally spaced ports formed in its wall all around the combustion chamber, each serving both as an inlet port and an exhaust port; an annular valve rotatably supported outside the cylinder controlling said ports; and means for imparting a step-wise rotary movement to said valve at suitable predetermined points in the cycle of the motor, the ports of the valve being so spaced that the cylinder ports are closed during the compression and explosion strokes of the motor.

2. In an internal combustion motor the combination of a cylinder having a plurality of equally spaced ports formed in its wall around the combustion chamber, each serving both as an inlet port and an exhaust port; an annular valve rotatably supported outside the cylinder controlling said ports formed all around the same; said valve having a series of alternated inlet and exhaust ports, the exhaust ports opening through a different surface of the valve to that through which the inlet ports open; and means for

imparting a step-wise rotary movement to 65 said valve at suitable predetermined points in the cycle of the motor, the ports of the valve being so spaced that the cylinder ports are closed during the compression and explosion strokes of the motor.

3. In an internal combustion motor the combination of a cylinder having a plurality of equally spaced ports formed in its wall around the combustion chamber, each serving both as an inlet port and an exhaust 70 port; an annular valve rotatably supported outside the cylinder controlling said ports formed all around the same, said valve having a series of alternated inlet and exhaust ports, the exhaust ports opening through a 75 different surface of the valve to that through which the inlet valves open; an annular exhaust manifold fitted to said valve to receive the exhaust, the valve rotating in contact with said manifold; and means for imparting a step-wise rotary movement to said valve at suitable predetermined points in the cycle of the motor, the ports of the valve being so spaced that the cylinder ports are closed during the compression and explosion 80 strokes of the motor.

4. In an internal combustion motor the combination of a cylinder having a plurality of equally spaced ports formed in its wall around the combustion chamber, each serving both as an inlet port and an exhaust 85 port; an annular valve rotatably supported outside the cylinder controlling said ports, said valve being provided with a series of alternated inlet and exhaust ports arranged 90 as follows; viz. an exhaust port, an inlet port, a blank space corresponding to two ports and repeat; and means for moving the annular valve at every stroke of the motor a distance equal to one quarter the distance between cylinder port centers.

5. In an internal combustion motor the combination of a cylinder having a port formed in its wall serving both as an inlet port and an exhaust port; an annular valve 95 rotatably supported outside the cylinder controlling said port formed all around the same, said valve having a series of alternated inlet and exhaust ports, the exhaust ports opening through a different surface of 100 the valve to that through which the inlet valves open; and means for imparting a step-wise rotary movement to said valve at suitable predetermined points in the cycle of the motor, the ports of the valve being so 105 spaced that the cylinder ports are closed during the compression and explosion strokes of the motor.

6. In an internal combustion motor the combination of a cylinder having a port formed in its wall and an exterior coned valve seat in combination with an annular valve controlling said port and fitted on said

coned valve seat; spring means holding said valve on its seat; and means for adjusting the tension of the spring means.

7. In an internal combustion motor the combination of a cylinder having a plurality of equally spaced ports formed in its wall around the combustion chamber, an annular valve rotatably supported outside the cylinder controlling said ports, said valve having

10 a series of alternating inlet and exhaust

ports; and means for imparting a step-wise movement to said valve at suitable predetermined points in the cycle of the motor.

Signed at Toronto, Ont., this 3rd day of April, A. D. 1916, in the presence of the two ¹⁵ undersigned witnesses.
